UNITED STATES PATENT OFFICE.

WILLIAM LEVIN, OF NEW YORK, N. Y.

DESIGN FOR A PICTURE-FRAME.

SPECIFICATION forming part of Design No. 17,944, dated December 13, 1887

Application filed October 6, 1887. Serial No. 251,761. Term of patent 3½ years.

To all whom it may concern:

Be it known that I, WILLIAM LEVIN, a citizen of the United States, residing in New York city, county and State of New York, have invented and produced a new and original Design for Picture-Frames, of which the following is a specification, reference being had to the accompanying drawings, forming part thereof.

10 In the annexed drawings, Figure 1 shows in elevation the corner part of a picture-frame embodying my design. Fig. 2 is a cross-section of the molding on line $x\ x$ of Fig. 1.

This design consists, mainly, in the bold 15 broad convex bead or member a , running all around the frame near the inner edge or rabbit, b , combined with the narrow raised bead c at the outer edge of the frame, and a broad flat recess or band, d , lying depressed between 20 the two. The broad raised convex member a of the design is carved or decorated with bold figures in relief, the most prominent of which consists of an underlying string, on which are seen occasional beads or bulbs f and large 25 petaled flowers g , with urn-shaped groups of radiating leaves h . Smaller leaves and petalled flowers are seen worked in among the larger features referred to. The narrow marginal bead c is ornamented with a corrugated 30 and beaded band, on which are superposed ro-

settes i at frequent intervals. The depressed band d between the bold convex member a and the marginal bead c is ornamented with rather shallow or flat carving of an arabesque character, consisting of heart-shaped foliated figures, as fully shown in the photograph.

35 This design gives a strong, novel, and pleasing effect, as may be seen in the photograph, where it will be noted that the member a is the highest, boldest, and most prominent part 40 of the frame, while the outerlying portion of the frame retreats or inclines back therefrom, and the bead c on the retreating front catches the light, while the broad depressed band d between the two is cast in shadow by the bold 45 member a , thus giving a richly lighted and shaded effect, which is artistic and effective in a high degree.

What I claim is—

The design for a picture-frame, consisting of 50 the raised or convex member a , having the figures $h\ g\ f$, the depressed band d , ornamented with heart-shaped figures, and the marginal bead c , ornamented with a rosetted band, substantially as herein described and 55 illustrated.

WILLIAM LEVIN.
